PORTABLE POWER OPERATED WOOD PLANE

Arthur N. Emmons, Nedrow, N. Y., assignor to The
Porter-Cable Machine Company, Syracuse, N. Y., a
corporation of New York

Application January 7, 1955, Serial No. 33,865

Term of patent 14 years

(Cl. D93—4)

FIG. 3

FIG. 2

FIG. 1

FIG. 5

FIG. 4

Figure 1 is a front elevational view of a portable power operated wood plane embodying my new design.

Figure 2 is a side elevational view looking to the left, Figure 1.

Figure 3 is a side elevational view looking to the right, Figure 1.

Figure 4 is a top plan view.

Figure 5 is a view in perspective.

I claim:

The ornamental design for a portable power operated wood plane, as shown.
